(57) CLAIM

We claim the ornamental design for a service cart, as shown and described.

DESCRIPTION

FIG. 1 is a perspective view of a service cart showing our new design;

FIG. 2 is a side view showing our new design shown in FIG. 1, the other side views being identical;

FIG. 3 is a front view showing our new design shown in FIG. 1, the back view being identical;

FIG. 4 is a top view showing our new design shown in FIG. 1; and,

FIG. 5 is a bottom view showing our new design shown in FIG. 1.

The broken lines in the figures are included for the purpose of illustrating environment and form no part of the claimed design.
